ARC LAMP

James H. Wagenhorst, Detroit, Mich.

Application January 14, 1929. Serial No. 332,471

9 Claims. (Cl. 176—115)

My invention relates to improvements in arc lamps, and has to do, more particularly, with arc lamps of a construction peculiarly fitting them for therapeutic use in hospitals or the like, although certain features of my invention may well be incorporated in arc lamps for other uses.

The chief object of my invention is to provide an arc lamp having a cabinet provided with a double reflector of such a nature that the light from the arc or arcs enclosed within the cabinet is directed through diverging reflectors upon two zones spaced on opposite sides of the apparatus, so that, for instance, the apparatus may be placed between two beds in a hospital and used to treat simultaneously patients lying upon the two beds.

A further object of my invention is to provide a simple and economical arc lamp construction which can be manufactured cheaply and yet is strong and efficient in operation.

A further object of my invention is to provide an arc lamp cabinet having vents in the upper portion of the reflector through which fumes from the arc may escape upwardly and, further, to provide above the reflector a housing for the operating mechanism provided with vents through which the arc fumes and the heated air from the resistances or rheostat constituting a part of the operating mechanism, may escape to the outside air.

A further object of my invention is to provide an improved dashpot construction for retarding the movement of the electrodes in a direction to draw the arc, which shall be very simple and cheap to manufacture.

Further objects, and objects relating to details and economies of construction and operation, will definitely appear from the detailed description to follow. In one instance, I accomplish the objects of my invention by the devices and means set forth in the following specification. My invention is clearly defined and pointed out in the appended claims. A structure constituting a preferred embodiment of my invention is illustrated in the accompanying drawings, forming a part of this specification, in which:

Figure 1 is a view in front elevation of an apparatus embodying my invention;

Fig. 2 is a view of this apparatus in end elevation;

Fig. 3 is a vertical sectional view through the upper portion of the apparatus, taken on the line 3—3 of Fig. 2;

Fig. 4 is a detail sectional view, taken on

the line 4—4 of Fig. 3, showing the support for the solenoid and the dashpot;

Fig. 5 is a fragmentary view, in side elevation, of the parts shown in Fig. 4;

Fig. 6 is a detail sectional view, taken on the line 6—6 of Fig. 3, showing the support for the stationary electrodes, the parts being sectioned around the clamping screw in order to show the insulation;

Fig. 7 is a detail sectional view taken on the line 7—7 of Fig. 3, and showing one of the clutches;

Fig. 8 is a detail sectional view taken on the line 8—8 of Fig. 7;

Fig. 9 is a vertical sectional view through the dashpot, taken on the line 9—9 of Fig. 4;

Fig. 10 is a vertical sectional view through the dashpot piston, taken on the line 10—10 of Fig. 9;

Fig. 11 is a horizontal sectional view, taken on the line 11—11 of Fig. 3, showing the electrode-operating levers and their mounting;

Fig. 12 is a detail sectional view, taken on the line 12—12 of Fig. 11, showing the connection between the upper end of the electrode-operating link and the operating lever; and

Fig. 13 is a sectional view, taken on the line 13—13 of Fig. 2, showing a detail of the construction of the supporting stand.

In the drawings, the same reference numerals refer to the same parts throughout the several views and the sectional views are taken looking in the direction of the arrows at the ends of the section lines.

In general, my invention consists in providing a frame which supports the cabinet and the operating mechanism of the lamp, and a cabinet having two diverging hood-like reflectors which merge into a central arc chamber, within which the arc or arcs are drawn between the cooperating electrodes of the lamp. The light from the arcs is thus directed through the reflector members upon spaced zones at opposite sides of the apparatus. The frame is preferably a U-shaped member with the reflector cabinet positioned between and secured to the legs of the frame. The operating mechanism of the lamp is suspended from the top member of the frame, with the movable electrodes depending through holes in the upper wall of the cabinet into the chamber in which the arc or arcs are formed. The cooperating stationary electrodes are supported within this chamber in alignment with the movable electrodes. The support for the stationary electrodes may well take the form of a brace

85

90

95

100

105

110

bar extending across the chamber within the cabinet and secured to the side walls of the cabinet and the side members of the frame. The operating mechanism may be suspended from the U-shaped frame by a U-shaped hanger, the upper ends of the hanger legs being fastened to the top member of the frame, while the bottom of the hanger is fastened to and supports the top wall of the reflector cabinet. It is important, in such a lamp, to provide some means for permitting the escape of fumes coming from the arcs and I have provided vents in the upper portion of the reflector cabinet through which these fumes may escape, and vents in the housing for the operating mechanism through which fumes and hot air coming from the lamp rheostat may escape.

Referring to the accompanying drawings, in which I have illustrated an apparatus constituting a preferred embodiment of my invention, the U-shaped frame member comprises the legs 10 and the top member 11. This frame member may well be made of a pipe bent to this form. The reflector cabinet is made of sheet metal, bent so as to form an arc chamber having a top wall 12, a parallel bottom wall 13 and parallel end walls 14 at right angles to the top and bottom walls. This forms a comparatively narrow but substantially rectangular chamber within which the arcs are located. From the sides of this chamber lead the two downwardly-directed and diverging reflector members, each having the substantially parallel and downwardly-inclined top and bottom walls 15 and 16, extending from the walls 12 and 13, respectively, and the end walls 17 which are inclined towards each other, as shown more particularly in Fig. 1. This reflector cabinet is of such construction that it can be made very cheaply and conveniently from two flat sheets of metal by notching and bending one sheet to form the bottom walls 13 and 16 and portions of the end walls 17, and bending the other sheet to form the top walls 12 and 15 and the end walls 17, overlapping the end wall portions of the two sheets and securing them together in any desired manner.

A brace bar 18 extends within the central chamber of the cabinet from one end wall 14 to the other. This brace bar has lateral flanges 19 at the opposite ends thereof, which lie against the inner sides of the end walls 14 and bolts 20 extend through the legs 10 of the frame, the end walls 14 and the flanges 19, as shown in Fig. 6, thus securing the frame and the brace bar together and fastening the reflector cabinet to the frame. The brace bar 18 thus serves as a stiffening and reinforcing member for the reflector cabinet and, also, affords supports for the stationary electrodes 21, the upper ends of which are located within the arc chamber, while the lower ends may depend therefrom through the openings 22 in the lower wall 13. Grooves or depressions 23 are formed, at the proper intervals, in the brace bar 18. A strip 24, of insulating material, is applied alongside the bar 18 and a pair of depressions 23, as shown in Fig. 6. An inner clamping member 25 having grooves or depressions in its ends to receive the electrodes 21, is held against the insulating strip 24 by the clamping screw 27. An outer clamping member 26 having grooves or depressions in its ends to receive the electrodes 21 is also applied to the clamping screw 27 so that the electrodes may be clamped between the members 25 and 26. The head of the clamping screw 27 is on the rear

side of the bar 18, insulated therefrom by the insulating washer 29. The shank of the bolt 27 passes through an insulating sleeve 30 in the bar 18, so that the clamping members 25 and 26 and the bolt 27 are insulated completely from the bar 18. A wing nut 28 screwed upon the outer end of the bolt 27 engages the outer clamping member 26 and thereby clamps the electrodes 21 in position upon the bar 18. In Fig. 3, I have shown two pairs of stationary electrodes, and it will be understood that Fig. 6 shows the clamping means for one pair only, a similar means being provided for clamping the other pair of electrodes in position.

The cooperating movable electrodes 31 are suspended by the operating mechanism of the lamp in alinement with the stationary electrodes, passing through holes 32 formed in the top wall 12 of the arc chamber. The operating mechanism of the lamp is suspended from the top member 11 of the frame by a U-shaped hanger having the legs or side members 33 and the bottom member 34. The upper ends of the legs 33 are bent laterally, at 35, and lie against the top member of the frame. Arms 36 extend downwardly from the ends of the portions 35 of the hanger. The hanger is secured to the top member of the frame by bolts 37, which extend through the portions 35. The bottom member 34 of the hanger lies upon the top wall 12 of the reflector cabinet and the latter is secured thereto by the bolts 38. In this way, the reflector cabinet is secured to the frame by the bolts 20 and, through the hanger, by the bolts 38.

An operating solenoid 45 is resiliently supported by the hanger, substantially centrally thereof, as shown in Fig. 3, so that vibrations of the coil due to the use of alternating current will not be transmitted to the rest of the lamp. Blocks 39 are secured to one side member 33 of the hanger by bolts 40. The bight of a U-shaped supporting member 41, of spring steel, passes through and is clamped in each block 39 and, at the outer end of each leg of the U-shaped member 41, there is an eye 42 receiving a bolt 43. There are three of these bolts 43 arranged equi-distantly around the solenoid 45 and their ends extend through the Y-shaped clamping bars 44 applied to the top and bottom of the solenoid. Nuts screwed on the ends of the bolts 43 fasten the solenoid to the spring steel supporting members 41 and, in this way, the solenoid is resiliently supported from the hanger. A laminated core 46 works in the solenoid and is connected to the inner ends of electrode-operating levers 47 by the springs 49, the upper ends of which are hooked into openings 48 in the inner ends of levers 47.

The electrode-operating levers 47 are pivoted on the depending arms 36 of the hanger, as shown in Figs. 3 and 11. Each lever is substantially U-shaped throughout the greater portion of its length and comprises the side members 47 and the bight 50. The outer ends of the side members are spaced from each other by a spacing sleeve 51 and a bolt 52. The corresponding hanger arm 36 extends between the side members 47, as shown in Fig. 11, and the lever is pivoted thereto by a pin 53 passing through said side members and arm. One side member of each lever is extended, at 54, beyond the other, and the inner ends of these levers cross, as shown in Figs. 3 and 11, and are connected loosely by a pin 55 carried by one arm 54 working in a slot 56 in the other arm. In

order to space these levers apart the proper distance, spacing sleeve 57 is provided, as shown in Fig. 11.

In order to retard movement of the operating levers in a direction to draw the arcs, I have provided a dashpot supported by the hanger. A piston rod 60 has its upper end connected to the inner end of one of the levers 47. The lower end of this piston rod is bent laterally at 61 and then 10 bent upwardly again at 62, extending within the open lower end of a dashpot cylinder 63. The upper end of this cylinder is closed by a cap 64 fitting snugly within it and secured thereto by a screw 68 which also fastens the cylinder to a saddle 69 secured to the hanger side member 33, by which means the dashpot is supported. A port 65 is provided in the cap 64 and closed by a valve formed by the head 66 of a rivet, the stem 67 of which is split, as shown in Fig. 9, 15 so as to prevent displacement of this element. This valve is sufficient to permit the escape of air upon upward movement of the piston within the cylinder, while preventing ingress of air upon the downward movement of the piston. 20 The piston 70 is preferably made of carbon and fits snugly within the cylinder 63. In order to connect it to the portion 62 of the piston rod, a tube 71 is inserted through the piston and the exposed outer end of this tube is flattened at 72, 25 so as to seal the tube completely. A loop 73, at the upper end of the portion 62 of the piston rod, is hooked through a hole formed in the flattened portion 72 of the tube. This makes a very effective connection between the piston 30 and the piston rod, which is, in fact, a universal connection, so as to prevent binding of the piston due to tilting of the piston rod in the operation of the mechanism.

Blocks 74, of insulating material, are located 40 on the upper wall 12 of the reflector cabinet and provided with openings 75 in line with the openings 32 of said wall, through which the movable electrodes depend. A clutch plate 76 is provided adjacent each of these blocks 74. The plate 76 has two openings therein, an enlarged opening 45 77, accommodating the left-hand electrode shown in Fig. 8, and a clutch opening 78 receiving the right-hand electrode 31 and of such dimensions that the edges of the hole will bind 50 and grip this electrode when the plate is tilted. An electrode-operating link 81 has an outwardly turned lower end 80 from which the laterally extending finger 79 projects through a hole in the end of clutch plate 76, as shown in Figs. 7 and 55 8. The upper ends of each pair of movable electrodes are clamped within the electrode holders 82 and the links or rods 81 extend through holes in and are guided by the rod guides 83 secured to said electrode holders.

60 A strip 84, of insulation, is wrapped around the bight 50 of each operating lever 47, as shown in Fig. 12. The clamping member 85 is clamped around this piece of insulation by a bolt 87 extending through the projecting ears 86 and is provided with a bearing extension 88 which receives the laterally-extending trunnion 89 upon the upper end of the corresponding clutch-operating rod 81. A cotter pin 90, passed through 65 the end of the trunnion 89, prevents its displacement from the bearing 88. In this way, a pivotal connection is provided very simply and conveniently between the operating lever and the corresponding clutch-operating link or rod, and, at 70 the same time, the lever is insulated from the 75

rod so that the operating circuit will not be short-circuited through the levers.

80 Slabs 92 of asbestos board, which serve as both heat and electrical insulation, are fastened to the side members 33 of the hanger and the resistance coils 91 are mounted on these slabs, for instance, by means of the bolts 93 carrying the clamping members 94 embracing adjacent turns of the coil, as shown in Fig. 5. The wires 95 leading to the outside mains are brought into 85 the switch 96 mounted on one side member 10 of the frame. From this switch, a wire 97 leads to the right-hand resistance coil 91, as shown in Fig. 3, and from the upper end of this coil a wire 98 leads to the electrode holder 82 for the left-hand pair of movable electrodes. The path of the current is from one of these movable electrodes to the corresponding stationary electrode and, from the electrode clamp for the left-hand stationary electrodes, a wire 99 leads to the lower end of the left-hand resistance coil 91. From the upper end of the left-hand resistance coil 91, a wire 100 leads to the upper end of the winding of solenoid 45 and, from the lower end of this winding, a wire 101 leads to the 100 right-hand electrode holder 82. From this electrode holder 82 the current passes through one or the other of the movable electrodes 31 and the corresponding stationary electrode 21 to the clamp for the right-hand stationary electrodes 105 and thence, by a wire 102, back to the switch 96.

105 The operating mechanism of the lamp is located in the space between the top member 11 of the frame and the top wall 12 of the reflector cabinet and is enclosed within the housing formed by the two hinged side members 103, each of which is provided with a stiffening flange 104, at its lower edge, which is connected by hinges 105 to the top portion of the reflector cabinet. The side and top portions of each 110 housing member 103 are grooved at 106 and 107 to fit the side and top members of the frame, as shown in Fig. 2, and they may be held in closed position by the screws 108 screwed into the top member 11 of the frame. Vent openings 109 are formed in the lower portions of the side members 103 substantially in line with the hanger, as shown in Fig. 3, and the upper corners are cut away to form the vent openings 110. Enlarged vents 111 are formed in the top wall 120 125 12 of the reflector cabinet, substantially in line with the resistance coils 91. By means of these vents, any fumes and hot air generated by the arcs may escape through the vents 111 into the housing for the working mechanism and, thence, 130 through the vent openings 109 and 110, in the housing, together with any heated air coming from the resistance coils, or other parts of the apparatus which are heated in use. The slabs 92, on which the resistance coils are mounted, 135 are so located with respect to the openings 109 that they act as baffles between the vents 109 and vents 111 so that fumes and heated air pass upwardly and are directed over the resistance coils and out the vents 110 at the upper 140 corners of the mechanism housing.

145 The arc lamp and its frame may either be suspended, or supported upon a stand, and, in the accompanying drawings, I have shown a form of stand particularly fitted for this apparatus. This comprises a U-shaped support having a bottom member 112 and side members 113. These side members are tubular and the legs 10 of the frame are adapted to telescope therein, as shown in Fig. 1. A series of holes 114 are 150

formed in the side members 113 and pins 115 may be inserted through selected ones of these holes, thus determining the height at which the apparatus will be supported and permitting some adjustment of the apparatus up and down. Legs 116 are provided which have their upper ends flattened at 117 so as to fit on opposite sides of the side members 113, to which they are fastened by the bolts 118, as shown in Fig. 13.

10 Notwithstanding the fact that the fumes are vented through the holes in the upper portion of the reflector cabinet, some heat will pass out through the reflector openings with the light and, if this is detrimental to the patient, it may be dissipated by providing in the bottom member 112 of the support an electric oscillating fan 119 connected by wires 120 with the switch 96. This fan is located in the central plane of the apparatus and, therefore, the arcs will be shielded by the lower walls 16 and 13 of the reflector cabinet, so as to prevent the air currents from the fan from blowing out the arcs.

15 It will be seen that I have provided an apparatus which is very well fitted for hospital use in that it can be placed between two beds and the two reflector members will direct the light from the arcs upon each bed, so that two patients can be given a light treatment simultaneously with this apparatus. Furthermore, the 20 light is all directed downwardly upon the bed, so that it will not get in the eyes of doctors, nurses or other attendants, and no one will be required to wear goggles during these light treatments except the patient. This apparatus is 25 very simple and compact and can be operated easily and may either be mounted on a stand, as shown, or suspended from the ceiling between the beds. Any fumes from the arcs escape upwardly through vents in the upper portion of the 30 reflector cabinet, so that the patients being treated are not subjected to any discomfort from fumes. The apparatus also contains a number of novel and important features of construction which make it simpler and cheaper to 35 build.

40 I am aware that the particular apparatus illustrated and described herein may be changed considerably without departing from the spirit of my invention, and, therefore, I claim my invention broadly, as indicated by the appended 45 claims.

Having thus described my invention, what I claim as new and useful and desire to secure by Letters Patent, is:

50 1. In an arc lamp, the combination of a U-shaped frame, a cabinet located between and secured to the legs of said frame and having two depending and diverging hood-like reflector members, the light-projecting axes of which are disposed at an angle of substantially ninety degrees with respect to each other and forty-five degrees with respect to the vertical plane through the center of the lamp, the inner portions of which merge in an arc chamber, electrode-operating mechanism carried by said frame, a movable electrode depending from said mechanism through the upper wall of said chamber, and a stationary electrode supported within said chamber in alignment with the movable electrode, whereby the light from an arc drawn between said electrodes is directed by said reflector members upon two zones at opposite sides of the apparatus.

55 2. In an arc lamp, the combination of a U-shaped frame, a reflector cabinet located be-

tween and secured to the legs of said frame, a U-shaped hanger secured to and depending from the top member of said frame and having its bottom member secured to the top wall of the reflector cabinet, an electrode-operating lever pivoted on said hanger, means for operating said lever, a movable electrode suspended from said lever and depending through the upper wall of said cabinet, and a stationary electrode supported within said cabinet in alignment with the movable electrode.

60 3. In an arc lamp, the combination of a U-shaped frame, a reflector cabinet located between and secured to the legs of said frame, a U-shaped hanger member secured to and depending from the top of said frame and secured to the upper wall of the reflector cabinet, an operating solenoid centrally carried by said hanger, an operating lever pivoted on said hanger, a core for said solenoid connected to one end of said lever, a movable electrode depending from the other end of said lever through the upper wall of the reflector cabinet and a stationary electrode supported within said cabinet in alignment with the movable electrode.

65 4. In an arc lamp, the combination of a frame, electrode-operated mechanism carried by said frame, a cabinet secured to said frame and having a downwardly-directed reflector member, a brace bar extending between the side members of said frame within said cabinet, a stationary electrode supported by said bar and a movable electrode depending from said operating mechanism through the upper wall of said cabinet in alignment with the stationary electrode.

70 5. In an arc lamp, the combination of a U-shaped frame, electrode-operating mechanism carried by said frame, a reflector cabinet located between and secured to the legs of said frame and having a downwardly-directed reflector portion, a brace bar extending between the legs of said frame within said cabinet, a stationary electrode supported by said bar and a movable electrode depending from said operating mechanism through the upper wall of said cabinet in alignment with the stationary electrode.

75 6. In an arc lamp, the combination of a U-shaped frame, electrode-operating mechanism carried by said frame, a reflector cabinet located between and secured to the legs of said frame and having two diverging hood-like reflector members, the inner portions of which merge in an arm chamber, a brace bar extending between the legs of said frame within said arc chamber, a stationary electrode supported by said bar and a movable electrode depending from said operating mechanism through the upper wall of said cabinet in alignment with the stationary electrode.

80 7. In an arc lamp, the combination of a U-shaped frame, electrode-operating mechanism carried by said frame, a reflector cabinet located between and secured to the legs of said frame and having a downwardly-directed reflector member, a brace bar within said cabinet having lateral flanges on the ends thereof lying against the end walls of said cabinet, bolts extending through said flanges, end walls and the legs of said frame, a stationary electrode supported by said bar and a movable electrode depending from said operating mechanism through the upper wall of said cabinet in alignment with the stationary electrode.

8. In an arc lamp, the combination of a U-shaped frame, a U-shaped hanger having side members, the upper ends of which are bent laterally along the top member of the frame 5 and secured thereto and provided with depending arms spaced laterally from the hanger side members, an operating solenoid supported by the hanger centrally thereof, a pair of levers pivoted on the hanger arms and having crossing 10 inner ends, a core for said solenoid connected to the inner ends of said levers, clutches suspended from the outer ends of said levers, movable elec-
trodes engageable by said clutches and stationary electrodes supported in alignment with the movable electrodes.
9. In an arc lamp, the combination of a U-shaped operating lever, a strip of insulating material wrapped around the bight of said lever, a clamping member clamped around said bight and insulation and having a bearing extension, and a clutch-operating link having its upper end bent laterally and journaled in said bearing. 80 85
